JOHN THOMSON, OF NEW YORK, N. Y.

ZIGZAG CARBON ELECTRIC RESISTER.

1,321,682.

Specification of Letters Patent.

Patented Nov. 11, 1919.

Application filed October 7, 1918. Serial No. 257,216.

To all whom it may concern:

Be it known that I, JOHN THOMSON, a citizen of the United States, and a resident of the borough of Manhattan, city of New York, county and State of New York, have invented certain new and useful Improvements in Zigzag Carbon Electric Resistors, of which the following is a specification.

The invention particularly relates to zig-zag, carbon, electric resistors for use in furnaces. Important objects of the invention are, to so form the resister and so dispose the alternating members which connect the zig-zags that a surface, or surfaces, of the resister will be maintained at a higher temperature than another surface, or surfaces; and to effect, in a single carbon body of given lineal dimensions, a greater resistivity than has hitherto been realizable.

20 In the drawings, Figure 1 shows a resister in plan; Fig. 2 is a side elevation thereof; Fig. 3 is an end elevation, as viewed from the bottom of Figs. 1 and 2; 25 Fig. 4 is a transverse section, as on the line A; and Fig. 5 is a view similar to Fig. 4 but of modified design.

The resister, B, is formed as from a carbon bar, whose original cross-section would preferably be square, and two of its opposing sides are planed to angles C, D, forming a wedge-like cross-section. The tapered side portions are then nearly entirely separated by forming a vertically and longitudinally extending central slot, E, passing from one end of the bar toward the other end, leaving thereat a relatively narrow portion, F. The zig-zags are produced by cutting alternating slits, H, which pass crosswise of the said central slot. The slits, H, extend vertically and transversely. A part of the slits, H, extends downwardly from the top surface of the resister toward 45 but short of the bottom surface of the resister leaving material, as at h', while the remainder of the slits H extends upwardly from the bottom surface toward but short of the upper surface of the resister leaving material, as at h''. In this wise each limb of the bar becomes a distinct resister connected in series by the end-section, or connector, F. The resister, as a whole, thus simulates in its appearance the prongs 50 of a tuning fork, each prong having a similar number of zig-zags. It may also

be referred to as a U-shaped resister each leg of said U-shaped portion having a number of zig-zags. Its separated ends may be provided with copper terminals, as I, J, which are symbolically denoted as connected to a power-circuit, K.

The object of forming the angular sides is to produce a progressive increase of current density, and a corresponding intensity 65 of temperature. Thus, which is best illustrated by Fig. 4, as the electric current passes from the top, r, to the bottom s, the cross-sectional area, due to the taper, is constantly diminishing, whereby the lower surface of the resister will be the hotter. This condition can be advantageously availed of in many cases, as by so setting or disposing the resister that its hotter portion is presented toward the body to be heated. This 70 effect has been previously realized by the present applicant, in the manner shown in his patent of August 8, 1916, No. 1,193,633, being therein particularly illustrated by Figs. 5, 6 and 7. In that case, however, the 75 increase of current-density is obtained by causing the current to traverse the connecting portion of a zig-zag along lines of different lengths, the section traversed by the current being uniform, while in the present 80 case the lines of current-traverse are of the same length but the cross-sectional area progressively increases or decreases.

The same densifying effect can be attained in a resister which is not centrally separated, as is shown in Fig. 5, whose side-angles are sharper than in Fig. 4. For example, in this case the maximum increase of current-density, and the corresponding heating effect along its bottom surface, 85 would be about 50 per centum greater than along its upper surface, with a progressive increase or decrease throughout the mass, as the case may be, from one surface to the other.

100 In the central slotted resister, as shown in the first four figures of the drawings, it is in fact a member having a compound circuit formed from a monolithic bar or block, possessing the advantages of the utmost 105 compactness, efficiency and endurance.

Obviously, where a wedge-like or other form of cross-section whereby to produce a progressively increasing or decreasing current-density, would not be advantageous, 110 a carbon bar of square or rectangular section may be centrally slotted and cross-

slotted in the manner herein described, thereby realizing the advantage in singular of obtaining the utmost length of circuit, having a restricted sectional area, with 5 the utmost compactness of structure.

What I claim is:

1. A zig-zag, carbon, electric resister having a longitudinal centrally disposed slot separating two contiguous series of zig-zags, 10 the said slot passing from one end of the carbon bar or block toward but not entirely through the other end thereof.
2. A zig-zag, carbon, electric resister, wedge-like in cross-section, in which the 15 slits which produce the zig-zags pass crosswise of the wedge, whereby the area of the connecting portions progressively increases or decreases in the direction traversed by the current.
- 20 3. A monolithic, compound, zig-zag, carbon, electric resister, formed by a bar or

block centrally slotted from one end toward but not through the other end and zig-zag slits crosswise of the said central slot.

4. A U-shaped electric resister each of the 25 legs of the U having a number of zig-zags.

5. A longitudinally-extending carbon resister member having a vertically and longitudinally extending slot which extends from one end of the member toward but not quite 30 to the other end thereof, thereby forming a U and each leg of the U comprising a number of zig-zags formed by alternately arranged slots that extend vertically and transversely of the resister member. 35

This specification signed and witnessed this 21st day of August, 1918.

JOHN THOMSON.
